UNITED STATES PATENT OFFICE

149,366

DESIGN FOR A TOY ROADSTER

Olai F. Larsen, Jr., Demarest, N. J., assignor to
Noma Electric Corporation, New York, N. Y., a
corporation of New York

Application April 3, 1946, Serial No. 128,229

Term of patent 3½ years

(Cl. D34—15)

To all whom it may concern:

Be it known that I, Olai F. Larsen, Jr., a citizen of the United States, residing at Demarest, in the county of Bergen and State of New Jersey, have invented a new, original, and ornamental Design for a Toy Roadster, of which the following is a specification, reference being had to the accompanying drawing, forming part thereof.

Figure 1 is a side view, Figure 2 is a top view, and Figures 3 and 4 are opposite end views, respectively, of a toy roadster showing my new design.

I claim:

The ornamental design for a toy roadster, as shown.

OLAI F. LARSEN, JR.
